UNITED STATES PATENT OFFICE.

DAMON GREENLEAF AND JOSEPH H. CROSBY, OF JACKSONVILLE, FLORIDA.

DESIGN FOR A KNIFE-HANDLE.

SPECIFICATION forming part of Design No. 24,450, dated July 2, 1895.

Application filed May 4, 1895. Serial No. 548,163. Term of patent 7 years.

To all whom it may concern:

Be it known that we, DAMON GREENLEAF and JOSEPH H. CROSBY, citizens of the United States, residing at Jacksonville, in the county of Duval and State of Florida, have invented and produced a new and original Design for Knife-Handles, of which the following is a specification, reference being had to the accompanying drawings, forming part thereof.

Our invention relates to a design for knife-handles.

Figure 1 is a view of one side of the handle, and Fig. 2 is a view of the reverse side thereof.

The leading feature of our design consists in the cluster of fruit, the stem, leaves, and the blossoms.

A is the handle, and B the ferrule secured thereon.

On either side of handle, A are represented orange-leaves *a*, orange-buds *b*, orange-blossoms *c*, and oranges *d*, all of which are so arranged as to form a spray.

Ferrule B has thereon a representation of the old city gates, cathedral, and watch-tower.

What we claim is—

The design for a knife handle, as herein shown and described.

DAMON GREENLEAF.
JOS. H. CROSBY.
